REFRIGERATION APPARATUS AND METHOD

William B. Anderson, West Springfield, Mass., assignor to Westinghouse Electric & Manufacturing Company, East Pittsburgh, Pa., a corporation of Pennsylvania

Application June 19, 1942, Serial No. 447,640

10 Claims. (Cl. 62—1)

This invention relates to refrigerating apparatus and more especially to a method of packaging such apparatus and methods for testing and shipping said packaged units on a mass production basis.

One object of the invention is to provide economically packaged refrigerating units.

Another object of the invention is to provide economically packaged refrigerating units and an improved means of testing the units in their packaged form.

A further object of the invention is to provide an improved method of testing refrigerating units.

A further object of the invention is to provide an improved method of shipping refrigerator units.

A still further object of the invention is to provide an improved method of determining the refrigerant charge in refrigerating units.

These and other objects are effected by my invention as will be apparent from the following description and claims taken in connection with the accompanying drawings, forming a part of this application, in which:

Fig. 1 is a side elevation of a refrigerating unit assembled in the packaged form of this invention;

Fig. 2 is a front elevation of the packaged refrigerating unit of Fig. 1;

Fig. 3 is a plan view of the refrigerating condenser and evaporator of Fig. 1;

Fig. 4 is a partial vertical section of the sealed casing of the motor-compressor unit;

Fig. 5 is a schematic view of the room in which the units are tested;

Fig. 6 is an elevation of a freight car with one side wall removed to show the method of supporting the refrigerating units in the car; and,

Fig. 7 is a section on the line VII—VII of Fig. 6.

Referring to the drawings for a description of the invention, the reference numeral 10 represents a plate-type condenser comprising an elongated channel-shaped plate of metal 11 and a metal tube 12 convoluted back and forth across the inner surface thereof and brazed thereto. The plate 11 has outwardly-turned edges 13, and a bracket 14 is secured by rivets 16 to the lower portion of the edges 13. The bracket 14 supports a hermetically-sealed casing 17 by means of three rubber supports 18. The casing 17 encloses a refrigerant compressor 15 and a motor 20 for driving the same and forms a sump for lubricating oil.

An evaporator 19 is secured to the upper portion of the plate condenser 10. The evaporator 19 is generally U-shaped and comprises a base 21, two legs 22 and 23, and front, back and top edges 24, 26 and 27. The evaporator 19 comprises two

U-shaped sheets of metal 28 and 29 in which depressions are formed to provide various refrigerating passages 30, 31, 32 and 33. The sheets 28 and 29 are welded together to provide a leak-proof structure. The refrigerating passages 31 run along the base 21 and along the legs 22 and 23 parallel to the edges 24 and 26 and are interconnected at the base by the cross passage 30. The narrow passages 31 communicate with the 10 relatively large, elongated passage 32 and with the somewhat smaller passage 33, each of which is adjacent and parallel to one of the edges 27 of the legs 22 and 23, respectively. The two passages 32 and 33 are interconnected by a tube 35. 15 The respective top edges 27 of the legs 22 and 23 are provided with lugs 40, which lugs are secured with bolts 34 to the condenser 10.

The compressor 15 in the casing 17 communicates with the upper end of the tube 12 by means 20 of a tube 36. The lower end of the tube 12 communicates with the lower portion of the passage 30 through a capillary impedance tube 37. The casing 17 communicates with the upper portion of the large refrigerant passage 32 through a suction tube 38. Power for the electric motor in the casing 17 is supplied through three insulated bushings 39 located in the walls of the casing 17. The refrigerant unit just described contains a refrigerant liquid so that when power is applied to the electric motor through the bushings 39, the compressor will compress and discharge refrigerant vapor through tube 36 into the tube 12 of the condenser 10 wherein the refrigerant vapor condenses to a liquid which flows 25 downwardly in the tube 12 and is delivered by the capillary tube 37 to the refrigerant passage 30. The refrigerant liquid flows into the passage 30 to fill the evaporator 19 to the level indicated by line 41, which level is hereinafter designated 30 as the "refrigerant liquid level."

When thus united together or packaged, the evaporator 19 is not in its normal operating position but is secured to the plate 11 of the condenser 10 by means of the lugs 40 which eventually 45 are used to secure the evaporator 19 to the upper wall of the insulated chamber of the refrigerator cabinet in which the unit is employed. In its normal operating position the edge 27 of the evaporator 19 is uppermost so that the two passages 32 and 33 form refrigerant headers. The 50 normal position of the evaporator 19 when the unit is assembled to a refrigerator cabinet is shown in Patent No. 2,279,272, issued April 7, 1942, to W. B. Anderson et al. The evaporator in its 55 normal operating position has edges 24 at its front, edges 26 at its rear and edges 27 at its top, the walls thereby defining a U-shaped chamber disposed in the normal position of the letter U.

In the manufacture of refrigerators, the factory which produces the refrigerating unit may

be located at a distance from the one in which the refrigerator cabinets are produced, so that an economical means of shipping the units is desirable. The units so packaged may be shipped without using any additional crating or packaging material by placing the units directly on supporting rails 46 provided for this purpose in suitably designed freight cars 47. This method of shipping is shown in Figs. 6 and 7. Heretofore, the units were shipped with the evaporators supported by brackets from the plate condenser, in the position it would normally be in when disposed in the refrigerator cabinet. By this improved method of shipping, the brackets, etc., for supporting the evaporator are dispensed with.

The refrigerating unit is preferably passed through the shop test in the packaged form shown in the drawings. During the shop test the unit is in the upright position, as shown in Figs. 1 and 2, with the edge 24 of the evaporator 19 approximately horizontal and uppermost. In this position, the refrigerating apparatus in the casing 17 and the condenser 10 are in their normal operating position. The shop test is made by running the bare unit for a predetermined period of time in a test room maintained preferably at a predetermined temperature and humidity.

Such a shop test is described in detail in Patent No. 2,188,303, issued to Charles E. Roberts on January 30, 1940. It may include the use of a chamber 49 in which the temperature and humidity is held at constant values by an air conditioning unit 51 controlled by the temperature-responsive element 52 and the humidity-responsive element 53. The refrigerating units may be moved through this chamber on a trolley 54 which forms a part of the assembly line on which the units are fabricated. At the end of the running period certain observations are made, and one of these is the height of the upper edge of the frost area which gathers on the evaporator 19. The upper edge is represented by the dotted line 42 in the drawings and will hereinafter be designated as the "frost line." During such a test the frost gathers at those areas of the evaporator which contain refrigerant liquid and usually spreads somewhat beyond the area containing the liquid depending upon the duration and character of the test. As shown in Figs. 1 and 2, it is located somewhat above the refrigerant liquid level 41 and comes to a peak at the base of the evaporator 19 adjacent the passage 30. This peak is caused by the refrigerant liquid and vapor spouting upwardly in passage 30 as it issues from the tube 31. If the refrigerant unit is charged with too much or too little refrigerant liquid, it is indicated by a too-high or too-low position of the frost line 42, respectively.

If the cooling unit 19 were in its normal operating position with the edge 27 uppermost during the shop test, the entire evaporator 19 would be covered with frost. The frost line would then be on the portion 43 of the suction tube 18 immediately adjacent the evaporator and would not accurately indicate the quantity of refrigerant liquid in the evaporator because the velocity of the refrigerant vapor passing through the tube 43 is comparatively high, so that entrained particles of refrigerant liquid are carried with it. These particles of refrigerant liquid refrigerate the tube 43 to such a degree that the frost may form thereon at areas remote from the refrigerant liquid.

The reason for the change in the frost line in the two positions of the evaporator 19 is as follows: When the evaporator 19 is in its normal

operating position with the edge 27 uppermost, the level of the refrigerant therein will be slightly below the large refrigerant passages 32 and 33. When the evaporator 19 is tilted so that the edge

24 is uppermost, a substantial portion of the refrigerant liquid will flow into the lower portions of the large passages 32 and 33 so that the refrigerant liquid level is at a comparatively lower point on the evaporator 19. It will be noted that in either position of the evaporator 19, the suction tube 38 withdraws refrigerant vapor from the upper portion of the evaporator 19. It is also obvious that my invention is not limited to the type of evaporator shown in the drawings.

15 It will be apparent from the above that this invention provides a convenient method of packaging the elements of a refrigerating unit for shipment. It will be further apparent that in the packaged form of the elements, as provided 20 by this invention, a more accurate determination of the quantity of refrigerant liquid in the unit is obtainable during the shop test of the packaged unit. Furthermore, the packaged unit 25 may be readily and cheaply shipped in the same condition as when tested, without the use of crates, etc.

While I have shown my invention in but one form, it will be obvious to those skilled in the art that it is not so limited, but is susceptible 30 of various changes and modifications without departing from the spirit thereof, and I desire, therefore, that only such limitations shall be placed thereupon as are specifically set forth in the appended claims.

35 What I claim is:

1. A packaged refrigerating unit comprising a condenser having a substantially vertical surface when in its normal operating position, a refrigerant compressor secured to said condenser in normal operating relationship therewith, an evaporator having a portion which is uppermost when the evaporator is in its normal operating position, and means securing said evaporator to the vertical surface of the condenser in such a position that said normally uppermost portion of the evaporator faces said surface of said condenser.

2. A packaged refrigerating unit comprising a rigid condenser, a refrigerant compressor secured to said condenser in normal operating relationship therewith, an evaporator having an upper portion, means for suspending the evaporator from its upper portion when in its normal operating position and means securing said evaporator by said suspending means to said rigid condenser at right angles to its relationship to said condenser during normal operation, whereby said condenser and evaporator are united with a minimum of extraneous fastenings into a unit suitable for testing and shipping.

60 3. A packaged refrigerating unit comprising a rigid condenser, a refrigerant compressor secured to said condenser in normal operating relationship therewith, an evaporator, means on the upper portion of said evaporator for suspending it in its normal operating position from a horizontal interior wall of a refrigerator cabinet, said evaporator being secured to said rigid condenser substantially directly by said suspending means in a relationship to said condenser and compressor at right angles to its relationship thereto during normal operation, whereby said condenser, compressor, and evaporator are united with a minimum of extraneous fastenings into a package suitable for testing and shipping.

4. The method of testing a refrigerating unit by operating said unit under controlled conditions, said unit comprising a condenser, a compressor, and an evaporator; said evaporator being so proportioned that, when in its normal operating position, the major portion thereof is covered with frost when said unit is operated under said controlled conditions, and when said evaporator is disposed at a certain angle to its normal operating position, a substantially smaller portion thereof is covered with frost when said unit is operated under said controlled conditions; said method comprising disposing the evaporator at said angle, operating said unit under said controlled conditions while said evaporator is in such position, and comparing the frosted areas of said evaporator with a predetermined standard.

5. The method of testing a mechanical refrigerating unit, said unit comprising a refrigerant compressor, a refrigerant condenser, and a refrigerant evaporator, tubing connecting said compressor, condenser, and evaporator into an operative refrigerating circuit, refrigerant liquid in said unit, said evaporator having refrigerant passages and a relatively larger refrigerant header, said method of testing comprising operating said unit with at least said evaporator in a humid ambient atmosphere and with said evaporator positioned at such an angle to its normal operating position that a substantial portion of the refrigerant passages are above the refrigerant liquid level in the evaporator and a substantial portion of the header is below said level, and comparing the frost line formed on the evaporator during said operating period with a predetermined standard.

6. The method of testing a mechanical refrigerating unit, said unit comprising a refrigerant compressor, a refrigerant condenser, and a refrigerant evaporator, tubing connecting said compressor, condenser, and evaporator into an operative refrigerating circuit, refrigerant liquid in said unit, said evaporator having refrigerant passages and a relatively larger refrigerant header, said method of testing comprising operating said unit for a predetermined time in an ambient atmosphere of substantially predetermined temperature and humidity while said evaporator is positioned at such an angle with its normal operating position that a substantial portion of the refrigerant passages are above the refrigerant liquid level in the evaporator and a substantial portion of the header is below said level, and comparing the frost line formed on the evaporator during said operating period with a predetermined standard.

7. The method of testing a mechanical refrigerating unit, said unit comprising a refrigerant compressor, a refrigerant condenser, and a refrigerant evaporator, tubing connecting said compressor, condenser, and evaporator into an operative unit, refrigerant liquid in said refrigerating unit, said refrigerant evaporator having small refrigerant passages and a larger refrigerant passage located above said small refrigerant passage when the evaporator is in its normal operating position, said method of testing comprising positioning said evaporator at an angle to its normal operating position so that at least a substantial portion of said small passages are at a higher level than a substantial portion of said larger passage, whereby the refrigerant liquid level in said evaporator is located further below the upper portion of the uppermost of any of said passages than during operation in its normal

position, operating said unit for a period of time in a humid ambient atmosphere, and comparing the height of the frost area formed on the evaporator during said period with a predetermined standard.

8. The method of testing a mechanical refrigerating unit, said unit comprising a refrigerant compressor, a refrigerant condenser, and a refrigerant evaporator, tubing connecting said compressor, conductor, and evaporator into an operative unit, refrigerant liquid in said refrigerating unit, said refrigerant evaporator having small refrigerant passages and a large refrigerant passage located above said small refrigerant passages when the evaporator is in its normal operating position, said method of testing comprising positioning said evaporator at an angle to its normal operating position so that at least a substantial portion of said small passages are at a higher level than a substantial portion of said large passage, whereby the refrigerant liquid level in said evaporator is located farther below the upper portion of the uppermost of said passages than during operation in its normal position, operating said unit for a predetermined period of time in an ambient atmosphere of substantially predetermined temperature and humidity, and comparing the height of the frost area formed on the evaporator during said period with a predetermined standard.

9. The method of packaging, testing, and shipping a refrigerating unit, said unit comprising a compressor, a condenser, and an evaporator, said evaporator having the major portion thereof covered with frost during operation of said unit with the evaporator in its normal operating position, packaging said unit by securing said compressor to said condenser in normal operating relationship therewith, securing said evaporator to said condenser in a test position so that when the condenser and compressor are in their normal operating position and the unit operated during test conditions, substantially smaller portions of said evaporator will be covered by frost, testing said packaged unit by operating the same with the condenser and compressor in their normal operating position and the evaporator in said test position and shipping said unit in said packaged form with said evaporator in said test position.

10. The method of packaging, testing, and shipping a refrigerating unit, said unit comprising a compressor, a condenser, and an evaporator having refrigerant passages and a refrigerant header above said passages when the evaporator is in its normal operating position, said method comprising packaging said unit by securing said compressor to said condenser in normal operating relationship therewith and securing said evaporator to said condenser in a test position so that when the unit is operated with the condenser and compressor in their normal operating position, more refrigerant liquid will be located in said refrigerant header than is present therein when the unit is operated with the condenser, compressor and evaporator in their normal operating position, whereby the refrigerant liquid level in said evaporator is lowered, testing said unit when so packaged by operating the same with the condenser and compressor in their normal operating position and the evaporator in said test position and shipping said unit in said packaged form, whereby the necessity of using additional packaging material is avoided.

WILLIAM B. ANDERSON.

CERTIFICATE OF CORRECTION.

Patent No. 2,331,099.

October 5, 1943.

WILLIAM B. ANDERSON.

It is hereby certified that error appears in the printed specification of the above numbered patent requiring correction as follows: Page 3, first column, line 66, claim 7, for "passage" read --passages--; and second column, line 10, claim 8, for "conductor" read --condenser--; and that the said Letters Patent should be read with this correction therein that the same may conform to the record of the case in the Patent Office.

Signed and sealed this 23rd day of November, A. D. 1943.

(Seal)

Henry Van Arsdale,
Acting Commissioner of Patents.
